US00D366503S

United States Patent [19]

Sines et al.

[11] **Patent Number:** **Des. 366,503**[45] **Date of Patent:** ****Jan. 23, 1996**[54] **BLACKJACK CARD DECK**

[75] Inventors: **Randy D. Sines**, Spokane, Wash.;
Steven L. Forte, Henderson, Nev.;
David A. Krise, Spokane, Wash.

[73] Assignee: **Sines & Forte**, Henderson, Nev.

[**] Term: **14 Years**

[21] Appl. No.: **28,882**

[22] Filed: **Sep. 23, 1994**

[52] U.S. Cl. **D21/45**

[58] Field of Search **D21/14-36, 42-47;**
273/236-285, 292-308

[57] **CLAIM**

The ornamental design for a blackjack card deck, as shown and described.

DESCRIPTION

FIGS. 1-52 are top plan views showing a set of cards comprising a blackjack card deck, showing our new design, being of conventional thickness, the bottom being either plain and unornamented, or covered with ornamentation which is not the subject of this invention; and,

FIGS. 53-104 are top plan views showing a second embodiment of the design shown in FIGS. 1-52.
